United States Patent

Des. 241,656

Patented Sept. 28, 1976

241,656

VIDEOTELEPHONE TRANSMITTER

Donald Michael Genaro, Haworth, and Thomas Joseph Kelly, Middletown, N.J., John Niel McGarvey, Drexel Hill, Pa., and Daniel Wescoat Tyler, Middletown, N.J., assignors to Bell Telephone Laboratories, Incorporated, Murray Hill, N.J.

Original design application Oct. 15, 1974, Ser. No. 514,401. Divided and this application June 25, 1975, Ser. No. 590,335

Term of patent 14 years

Int. Cl. D14—03

U.S. Cl. D26—14 A

FIG. 1

FIG. 2

FIG. 3

FIG. 4**FIG. 5**FIG. 1 is a left front perspective view of a video-telephone transmitter showing our new design;

FIG. 2 is a front view of the transmitter shown in FIG. 1;

FIG. 3 is a right side view of the transmitter shown in FIG. 1;

FIG. 4 is a rear view of the transmitter shown in FIG. 1; and

FIG. 5 is a top plan view of the transmitter shown in FIG. 1.

This application is a division of our co-pending design application, Ser. No. 514,401, filed Oct. 15, 1974, and now Patent No. D. 237,801.

We claim:

The ornamental design for a videotophone transmitter, substantially as shown and described.
